Primary Examiner — Daniel J Domino*Assistant Examiner* — Samina Vieth(74) *Attorney, Agent, or Firm* — David L. Hoffman;
 Nolan Heimann LLP**CLAIM**

I claim the ornamental design for an antenna with boom with sectors with looped directors, as shown and described herein.

DESCRIPTION

FIG. 1 is a left side and front perspective view of my antenna with boom with sectors with looped directors;

FIG. 2 is a right side and front perspective view thereof;
 FIG. 3 is a left side view thereof, a right side view being a mirror image thereof;

FIG. 4 is a front view thereof;

FIG. 5 is a rear view thereof;

FIG. 6 is a top view thereof; and,

FIG. 7 is a bottom view thereof.
